BOTTLE OPENER

Raymond M. Brown, Newport News, Va.

Application December 28, 1932, Serial No. 649,224

4 Claims. (Cl. 65—48)

This invention relates to bottle openers, and is particularly designed to serve as a combination instrument to effect the removal of crown caps from bottles and of corks from bottle necks.

5 The invention is designed for use in hotels and similar places to avoid the constant marring of furniture by the attempts of guests to remove corks and caps from bottles by applying them to the edge of furniture, radiators, etc.

10 The object of the present invention is to provide a combination cap remover and cork extractor which can be fixed securely to a vertical surface and at a convenient height for use.

15 Another object of the invention is to provide a device of this character which can be very cheaply manufactured and which can be very readily assembled and positioned in any desired and suitable location.

20 Other objects of the invention will become apparent as the detailed description thereof proceeds.

In the drawings:

Figure 1 is a perspective view of one form of the invention;

25 Figure 2 is a side elevation of the device shown in Figure 1;

Figure 3 is a central vertical section through the device showing the cork removing part thereof in operative position;

30 Figure 4 is a front elevation of a modified form of the invention;

Figure 5 is a vertical section taken on the line 5—5 of Figure 4;

35 Figure 6 is an elevation of still another modification of the invention;

Figure 7 is a vertical section taken on the line 7—7 of Figure 6;

Figure 8 is an elevation of another modification of the invention;

40 Figure 9 is a vertical section taken on the line 9—9 of Figure 8;

Figure 10 is a vertical longitudinal section through a further modification of the device; and

45 Figure 11 is a vertical section through another modified form of the invention.

The various forms of the invention illustrated herein constitute improvements on the bottle opener disclosed in my United States Patent No. 1,702,149, February 12, 1929.

50 One of the most important improvements in the present invention over that disclosed in the patent, resides in the elimination of projecting lugs on the castings forming the body of the device, whereby the castings are rendered much

easier to grind and polish. In my patented device the corkscrew had to be manually raised and locked in inoperative position in order to adapt the device for use in the removal of crown caps from bottles. In the present invention the cork remover is held by gravity always in inoperative position, and out of the way of the crown cap remover; but is adapted to be very readily moved to position where it can be operated in the usual manner.

5 In the form of the invention shown in Figures 1, 2 and 3, the bottle opener comprises a base 1 adapted to be secured to a flat surface. The base 1 is formed in a single casting having a lower flat plate 2 aligned with an upper flat plate 3, both of 15 said plates being provided with apertures to receive screws 4, or other devices for securing the base 1 to any substantially vertical plane surface, such as the wall 5 or any other substantially vertical surface.

10 The base 1, between the plates 2 and 3, is provided with a hollow forwardly projecting recessed portion 6, provided at its outer edge with an annular flange 7 adapted to impinge against the lower edge of the rim of a crown cap in common use on narrow neck bottles. The rear end of the portion 6 has a lug 8 projecting at an obtuse angle from and formed integral with the lower plate 2. This lug 8 forms a fulcrum adapted to contact with the top of a crown cap; and is spaced relative to the annular flange 7 so that a bottle neck with a crown cap thereon may be conveniently located to effect removal of the cap in the well known manner.

15 The intermediate part 9 of the base member 1, between the plate 3 and the recessed portion 6, is provided with a slot 10 extending substantially throughout its entire length, and merges with a boss 11 formed integral with the plate 4. The boss 11 is apertured transversely to receive a pin 12 forming a pivot axis for the substantially cylindrical end 13 of a corkscrew 14.

20 From inspection of Figures 1, 2 and 3, it will be apparent that the corkscrew 14 in this form of the invention is designed to hang by gravity in a substantially vertical position back of the intermediate portion 9, and with its point 15 protected by the lug 8. The slot 10 is shaped to conform with the general outline of the corkscrew 14 and is of such length as to permit the corkscrew 14 to 25 swing outwardly from its vertical position through the slot 10 and into the operative position shown in Figure 3 of the drawings. The slot 10 extends throughout the length of the intermediate portion 9 and part way up through the boss 11 so 30

that the upper end 16 of the slot forms a stop to limit the outward swing of the corkscrew 14.

In the form of the invention shown in Figures 4 and 5, the casting 1' is identical in every respect with the base member 1 of the other form of the invention except that it is provided at the lower end of the slot 10' with a small stop 17 forming the bottom wall of a recess 18 adapted to receive the point of the corkscrew 14'. In this form of the invention, the corkscrew 14' is more readily moved into operative position, while at the same time the point of the corkscrew is fully protected and is in such position that it cannot catch on extraneous objects.

In the modification shown in Figures 6 and 7 of the drawings, the base 1' is identical with that illustrated in Figure 1. The only change occurs in the corkscrew which is extended at its upper end and bent to form a handle 20 projecting through the slot 10' to facilitate the rotation of the corkscrew 14' about the pivot pin 12 whenever it is desired to move it from the full line inoperative position shown in Figure 7 of the drawings to the operative position indicated by the dotted line in the same figure. Where the handle 20 is used, it is necessary to extend the slot somewhat further up around the boss 11 so that the upper end 16 of the slot shall act as a stop to contact with the handle 20 and limit the outward swing of the corkscrew 14' to proper operative position.

In the modification shown in Figures 8 and 9, the base member 1' is identical with the base shown in Figures 4 and 5 of the drawings. That is, the forwardly projecting portion is provided with a stop 17 and recess 18 to receive the tip of the corkscrew 14'. The corkscrew 14 is exactly like the corkscrew 14' shown in Figure 7 of the drawings. The upper end of the slot is continued around the boss 11, and terminates in proper position to serve as a stop for the handle 20 when the corkscrew is in the operative position shown by the dotted lines in Figure 9.

In the modification shown in Figure 10, the base of the device is exactly like that shown in Figure 1. The corkscrew may take either of the forms shown in Figure 3 or Figure 7. In this form of the invention a bridge 21 is fixed across the base 1 below the slot 10 to form a stop for the corkscrew. This bridge is located so as to hold the corkscrew out of parallelism with the wall 5 and with its point protected by its lug 8.

In that form of the invention illustrated in Figure 11, the base 1 is constructed in the same simple form as that shown in Figures 1 to 3, but the corkscrew 16 is provided beyond its pivotal connection 12 with a rear extension 17 so disposed as to abut against the support to which the base may be attached, when the corkscrew is in the inclined position as shown, leaving room behind the corkscrew for the insertion of a finger so that the corkscrew may be pushed through the slot 10 to a position forwardly of the base.

It is thought that the invention and numerous of its attendant advantages will be understood from the foregoing description and it is obvious

that numerous changes may be made in the form, construction and arrangement of the parts without departing from the spirit or scope of my invention, or sacrificing any of its attendant advantages; the forms herein described being preferred embodiments for the purpose of illustrating my invention.

What I claim is:

1. Wall type bottle closure remover comprising an integral base member formed with upper and lower lugs adapted to be secured to a flat surface and having the intermediate portion bent outwardly, bridging a space between said lugs, said outwardly bent portion having a front face formed with a longitudinal slot opening into said space, and a corkscrew element freely pivoted to said base member adjacent the top of said slot, in a position to swing by gravity in a plane passing through said slot and having a repose position in which its point is within the bounds of said outwardly bent portion.

2. Wall type bottle closure remover comprising an integral base member formed with upper and lower lugs adapted to be secured to a flat surface and having the intermediate portion bent outwardly, bridging a space between said lugs, said outwardly bent portion having a front face formed with a longitudinal slot opening into said space, and a corkscrew element freely pivoted to said base member adjacent the top of said slot, in a position to swing by gravity in a plane passing through said slot and having a repose position in which its point is within the bounds of said outwardly bent portion, said corkscrew element being formed with means exterior to said slot for tilting the corkscrew element to bring its point outside of the bounds of said outwardly bent portion.

3. Wall type bottle closure remover comprising an integral base member formed with upper and lower lugs adapted to be secured to a flat surface and having the intermediate portion bent outwardly, bridging a space between said lugs, said outwardly bent portion having a front face formed with a longitudinal slot opening into said space, a corkscrew element freely pivoted adjacent the top of said slot so as normally to dangle within the space bridged by said outwardly bent portion, and swingable through said slot, and a stop on said base member to prevent said corkscrew element hanging vertically.

4. Wall type bottle closure remover comprising an integral base member formed with upper and lower lugs adapted to be secured to a flat surface and having the intermediate portion bent outwardly, bridging a space between said lugs, said outwardly bent portion having a front face formed with a longitudinal slot opening into said space, a corkscrew element freely pivoted adjacent the top of said slot so as normally to dangle within the space bridged by said outwardly bent portion, and swingable through said slot, said corkscrew element being provided with means exterior to said slot for swinging said element to a position in which its point is outside of said slot.

RAYMOND M. BROWN.
